UNITED STATES PATENT OFFICE.

THOMAS BURKHARD, OF BROOKLYN, NEW YORK.

CONFECTIONER'S KETTLE.

SPECIFICATION forming part of Letters Patent No. 476,917, dated June 14, 1892.

Application filed December 14, 1891. Serial No. 414,903. (No model.)

To all whom it may concern:

Be it known that I, THOMAS BURKHARD, of Brooklyn, in the county of Kings and State of New York, have invented a new and useful Improvement in Candy-Kettles, of which the following is a specification.

My invention relates to an improvement in candy-kettles in which provision is made for both cooking and cooling the candy.

10 A practical embodiment of my invention is represented in the accompanying drawing, which shows a kettle in vertical section, with the heating or cooling coils in operative position relative thereto.

15 The body of the kettle is represented by A, and is provided at its bottom with a trap-door a , hinged to the bottom at a' , and provided at its free end with a clamp-nut a^2 and bolt a^3 for closing it liquid-tight.

20 Within the body of the kettle there are located an inner pipe-coil B and an outer pipe-coil B', spaced from each other and from the interior wall of the kettle. Pipes b and b' , leading to the coils B and B', pass through

25 the bottom of the kettle a short distance apart from each other, and are united outside by a connection B^2 . One of the pipes— b , for example—is continued and enters a cross-pipe C, provided on one side of the juncture of the

30 pipe b therewith with a cock c and upon the opposite side of said juncture with a cock c' . Pipes b^4 and b^5 , communicating with the opposite ends of the coils B and B', extend through

35 the side of the kettle at its upper portion and are connected outside of the kettle by a connection b^6 , one of the pipes— b^4 , for example—being continued beyond the connection b^6 and provided with a cock c^2 , and the connection b^6 , being continued beyond its juncture with

40 the pipe b^4 , is provided with a cock c^3 .

In addition to the coils within the kettle A, I further provide the kettle with an exterior coil B², located in proximity to the outer surface of the body of the kettle and conveniently

45 held in position by means of straps D, riveted or bolted to the kettle, as at d , at points intermediate of the winds of the coil and looped around the winds. The straps D may be continued from the top to the bottom of the coil,

as represented at the right of the body of the 50 kettle in the drawing, or they may be made to embrace the winds at intervals from the top to the bottom of the coil, as represented at the left of the body of the kettle in the drawing. The exterior coil B² communicates 55 at its lower end with a connection b^2 and at its upper end with a connection b^6 . The connection b^2 , common to the pipes of the three coils, is provided with a petcock c^4 .

In operation, when it is desired to cook the 60 candy within the kettle the cocks c , c^2 , and c^4 are closed and the cocks c' and c^3 are opened. Steam entering through the cock c^3 or the pipe in which it is located will pass through the connection b^6 into the three coils B, B', 65 and B², and thence through the connection b^2 into the cross-pipe C and out through the exhaust-cock c' or pipe in which it is seated. When it is desired to cool the candy within the kettle, the cocks c' and c^3 are closed and 70 the cocks c and c^2 opened. Water entering through the cock c or the pipe in which it is located will pass upwardly through the three coils and escape through the cock c^2 or pipe in which it is located. The cock c^4 may be 75 utilized at any time as a drain-cock.

By the above arrangement of pipes I am enabled to quickly cook a body of candy and as quickly cause it to congeal, the transition from cooking to cooling being effected by a 80 simple turning of the cocks.

What I claim is—

The combination, with the body of the kettle, of a plurality of series of pipe-coils, one of said series extending upwardly and downwardly within the body of the kettle and another of said series extending upwardly and downwardly along the exterior of the kettle and in proximity thereto, exterior connections common to the interior and exterior series of 85 coils, and cocks for regulating the transmission of hot and cold mediums at pleasure through the coils, substantially as set forth.

THOMAS BURKHARD.
